DESIGN FOR A COLLAPSIBLE CARTON

Stuart M. Andrews, Brooklyn, N. Y., assignor to
P. L. Andrews Corporation, Glendale, L. I.,
N. Y., a corporation of New York

Application March 1, 1935, Serial No. 55,667

Term of patent 3½ years

To all whom it may concern:

Be it known that I, Stuart M. Andrews, a citizen of the United States, residing at Borough of Brooklyn, county of Kings, in the city and State of New York, have invented a new, original, and ornamental Design for Collapsible Cartons, of which the following is a specification, reference being had to the accompanying drawing, forming part thereof.

In said drawing, Fig. 1 is a side elevation, Fig. 2 is a top plan view, Fig. 3 is a front end elevation, and Fig. 4 is a rear end elevation of a collapsible carton, showing my new design.

I claim:

The ornamental design for a collapsible carton, as shown.

STUART M. ANDREWS.
